HAIR CURLER WITH ELECTRIC ATTACHMENT

Salvatore Robert Salvio, New York, N. Y.

Application November 6, 1934, Serial No. 751,754

9 Claims. (Cl. 132—36)

This invention relates to improvements in hair curlers and has more particular relation to improvements in combined hair curlers and dryers.

One of the principal objects of the invention is to provide a hair curler which not only grasps and curls the hair, but at the same time, and with the same operation, locally applies a curling or setting lotion.

A further object of the invention is to provide a hair curler which may be employed for curling the hair either with or without the application of heat.

A still further object of the invention is to provide an improved hair curler which may be applied to the hair and heated after being so applied.

A still further object of the invention is to provide an improved hair curler which may be applied to the hair along with a chemical solution which, when dried, sets the hair in its curled condition.

The invention also has other objects, all of which will be hereinafter more particularly set forth and claimed.

25 In the accompanying drawing,

Figure 1 represents a side elevation of my improvements applied to a woman's hair.

Figure 2 represents a perspective view of one of my improved curlers; the parts being separated by pressure.

Figure 3 represents a detail perspective view of one of the solution tubes.

Figure 4 represents a detail vertical section of one of the tubes applied to one of the holding bails.

Figure 5 represents a detail perspective view of one of the insertable solution wicks.

Figure 6 represents a side elevation of one of the solution tubes being saturated with the solution.

Figure 7 represents a perspective view of a modified form of my invention; the parts being separated by pressure, and

Figure 8 represents a further modified form of a solution holding strip for application to one of the pivoted bails.

Described in general terms, the invention comprises two clamping members 1 and 2 pivoted at the point 3 and normally forced together by a leaf spring 3a near said pivotal pin 3, this structure being old and well-known in the art.

The member 1 is tubular, while the member 2 is semi-circular so as to lie about the tube 1 when the two members of the curler are closed. The member 1 is formed with a series of perforations

4 and a series of external criss-cross grooves 5. The interior surface of the member 2 is also formed with shallow criss-cross grooves 5a. Apertures 5b are formed in the member 2. The office of these grooves in both of the members is to hold liquid which is introduced just prior to the curling operation. The interior of the member 1 is of sufficient size to allow the introduction of an electrical heating element 6, shown in Figure 1. The heating elements 6 are of any desirable construction containing heating resistances, and are connected by double cords 7 with a source of electricity. These cords 7 are all bound into one cable 7a, as shown in Figure 1, and the negatives and positives connected together whereby the whole number of wires may be supplied with current from the ordinary house socket.

As it is particularly desirable to supply the part of the hair being curled with a chemical composition or solution which, when dry, will stiffen and set the hair into the desired curl, I provide a series of small fabric tubes 8 preferably composed of gauze. Each of these tubes is provided at one end with an elastic 9 which acts to hold the tube in position as hereinafter described. The opposite end of each of the tubes 8 is provided with a soft metal clamp 10, for a purpose hereinafter described.

A holding bail 11 has its opposite ends pivoted upon the journal pin 3. This bail is arranged to receive the fabric tube 8 thereon, as shown in the drawing. When so applied, the elastic 9 prevents the tube 8 from dropping off the bail when the fabric is being dipped into the chemical solution and before the soft metal clamp 10 is clamped in position.

After the hair has been clamped between the members 1 and 2, and the hair wound about both members 1 and 2, the bail is brought towards the assembled members after first having the tube saturated and then clamped tightly down upon the hair by binding the extended ends of the clamp 10 about both of the members 1 and 2.

The treated solution with which the tube 8 is saturated is thus transferred to the hair at the point where the curl is to be formed.

Further, the solution which has been caught in the shallow grooves of the members 1 and 2 is also transferred to the hair, and the entire curl thus saturated with the solution whereby the hair about the members 1 and 2 will be softened and finally caused to dry with the curl held more or less permanently in position because of the stiffening qualities of the solution.

As at times the above process does not provide

sufficient of the setting solution, I provide a stem-like wick 12 having a handle 13 at one end. This wick may be dipped in the setting solution and placed within each one of the members 1, 5 after the curl has been wound thereon.

After this operation has taken place, the wick may be withdrawn and the curl either allowed to dry naturally or artificially by the introduction of the electric heating element 6.

10 It will, of course, be understood that before the curl is wound about the sections 1 and 2, the curler is dipped into the solution and retains considerable of the solution which is trapped in the apertures 4 and 5b and the grooves 5 and 5a.

15 The handle of each of the sections 1 and 2 is provided with a rubber cap 14a. The office of these caps is to prevent the ends of the handles irritating the scalp or the face when the curlers are worn at night by a sleeper.

20 As it is desirable at times to apply more of the setting fluid to the portion of the hair to be curled, I contemplate also using two of the tube holding bails 11, as shown in Figure 7, the extra bail being also journaled by its free ends 25 on the pin 3. This form of the invention enables two of the fabric tubes to be saturated with the setting solution. When the curl is formed with this modification of the invention, the setting fluid is applied to the curl on both sides in addition to the trapped solution which is located in the different trapping grooves and which ultimately finds its way through the apertures 4 to the curl.

Through my improved invention, the curl is 35 not only moistened internally but also externally with the setting fluid.

In Figure 8 I have shown a modified form of the solution holding fabric. This form includes a flat fabric strip 14 with one of the flexible metal 40 strips 15 secured thereto at each end. In this form of the invention, the fabric is secured over either one or both of the bails 11 as desired.

After the curls are wound upon the members 1 and 2 and the bails applied in position, it is 45 sometimes desirable to apply heat to the interior of the member 1. This I contemplate doing by the devices shown in Figure 1. These devices comprise a series of resistance pencils having interior insulated heating resistances and connected in circuit with both the positive and 50 negative wires of the house circuit.

It will be seen from the above that the curls may be all applied to the hair and the heating element 6 applied to the interior of the tubes 1 55 without disturbing the curls. These heating elements may be withdrawn at any time after the parts are sufficiently heated. This is particularly desirable as the curls may be first formed, the parts then heated by the application 60 of the pencil 6, the pencils then withdrawn and the remainder of the drying process allowed to proceed by natural evaporation while the user is asleep at night.

It will, of course, be understood that the pencil 65 6 may remain in position until the curls are entirely dry if desired to quickly dry the hair.

A particularly desirable feature of the present invention resides in the fact that all of the hair 70 does not have to be moistened, but only the curl itself, and the curling operation can thus be accomplished more quickly and with a minimum of trouble.

With this improved curling process with its

"setting" feature, curls may be formed in the shortest possible time if it is desired to curl the hair without waiting for the natural process of drying overnight. For instance, as its use in preparing the hair rapidly for a special occasion. 5

What I claim is:

1. In a combined curling and setting device, the combination with a tubular member having apertures and solution trapping grooves, of a clamping device movable in relation to the tubular member for clamping the curl to the latter. 10

2. In a combined curling and setting device, the combination with a tubular member having apertures and trapping grooves, of a clamping member also having apertures and trapping 15 grooves and pivoted to the first mentioned member and means for securing the two members together with the curl thereon.

3. In a combined curling and setting device, the combination with perforated tubular member 20 having solution trapping grooves and means for clamping the hair thereto movably mounted on said tubular member and an electric heating element arranged to be inserted within the tubular member after the curl is formed. 25

4. In a combined curling and setting device, the combination with a perforated tubular member having solution trapping grooves, of a perforated pivoted guard also having solution trapping grooves, a pivoted bail, an absorbent tube arranged to be slipped over the bail and secured thereto and means connected to the tube for securing all of the parts together after the curl is formed. 30

5. In a combined curling and setting device, the combination with pivoted curling elements about which the hair is to be wound, of a movable part pivotally secured to said elements for holding the curl in position and absorbent material attached to and carried by said movable part to be moved into contact with the formed curl as desired. 35

6. In a combined curling and setting device, the combination with pivoted curling elements about which the hair is to be wound, of a movable part pivotally secured to said elements for holding the curl in position, absorbent material attached to and carried by said movable part to be moved into contact with the formed curl as desired, and a clamp attached to the absorbent material and arranged to secure the material to the pivoted curling elements. 45

7. In a combined curling and setting device, the combination with a tubular member, of a hair clamping member movable in relation thereto, a curl holder and an absorbent device carried by the curl holder and clamping means carried by the absorbent device and arranged for clamping the absorbent device against the curl after the latter is formed. 55

8. In a combined curling and setting device, the combination with two pivotally connected members, of a bail pivoted to said members, an absorbent device carried by the bail and provided with a means arranged to clamp about the free ends of the two clamping members. 60

9. In a combined curling and setting device, hair curling members movable towards and away from each other, and one of which is formed with solution trapping grooves, and means for clamping said members in contact with each other. 70

SALVATORE ROBERT SALVIO.
